UNITED STATES PATENT OFFICE.

JAMES L. MCQUARRIE, OF CHICAGO, ILLINOIS, AND ALBERT M. BULLARD, OF NEW YORK, N. Y., ASSIGNORS, BY MESNE ASSIGNMENTS, TO WESTERN ELECTRIC COMPANY, INCORPORATED, A CORPORATION OF NEW YORK.

SEMIMECHANICAL TELEPHONE-EXCHANGE SYSTEM.

Application filed February 5, 1907, Serial No. 355,884. Renewed April 22, 1909. Serial No. 491,601.

To all whom it may concern:

Be it known that we, JAMES L. MCQUARRIE, of Chicago, Cook County, Illinois, and ALBERT M. BULLARD, of New York, New York County, New York, citizens of the United States, have invented a certain new and useful Improvement in Semimechanical Telephone-Exchange Systems, of which the following is a full, clear, concise, and exact

10 description.

Our invention relates to a telephone system wherein the operator answers a call in the usual way by uniting her connecting circuit with the calling line, and mechanical switching mechanism completes the connection by uniting the connecting circuit with the called line, and has for its object to provide an improved arrangement of circuits and apparatus for facilitating the work of 15 the operator in completing connections between subscribers' lines.

Our invention relates more specifically to a semi-mechanical telephone exchange system in which means is provided whereby an 20 operator's sender or controlling device is adapted to be associated with one of a plurality of connecting circuits when such connecting circuit is taken for use.

In accordance with one feature of our invention, we provide means, in connection with a plurality of connecting circuits for interconnecting subscribers' lines, whereby a number of senders or controlling devices, less than the number of connecting circuits, 25 will suffice for the expeditious and accurate operation of the system, and means whereby a connecting circuit, upon being taken for use, will have automatically associated therewith a sender or controlling device to 30 control the line selection, and upon the completion of such selection have such sender or controlling device dissociated therefrom.

Our invention further involves means whereby one of a plurality of senders or controlling devices will be maintained normally accessible to a plurality of connecting circuits, means whereby upon the taking of one of the connecting circuits for use the sender or controlling device will be appropriated thereto and a second sender or con-

trolling device rendered accessible to the remaining connecting circuits, means whereby if a second connecting circuit is taken for use before the first sender or controlling device has completed its operation the second 55 sender or controlling circuit will be appropriated by the second connecting circuit and means whereby the senders or controlling devices when they have completed their operation will be again restored to condition 60 ready to serve some other connecting circuit.

The present invention is capable of especially advantageous use in connection with the telephone system forming the subject-matter of our application for patent for telephone exchange system, Serial No. 336,401 65 filed September 27th, 1906, wherein the operator answers a call in the usual manner by uniting her connecting circuit with the line of the calling subscriber by means of a connection switch, and is provided with mechanical switching mechanism for completing the connection of her connecting circuit with a desired line, said switching mechanism being controlled by sending apparatus 70 adapted to be set by the operator to cause the said switching mechanism to automatically unite said connecting circuit with the called line.

In the said system, a single sending apparatus is provided to serve a number of connecting circuits. Under ordinary traffic conditions, such single sending apparatus is adequate, but there are times when calls come too fast to enable one sending apparatus to 80 serve the several connecting circuits, inasmuch as the sending apparatus must necessarily occupy a definite interval of time in controlling the selective operations of the switching mechanism.

In accordance therefore with the present invention, a number of sending outfits or senders may be provided for use by a given group of connecting circuits; each connecting circuit is provided with a sender-seizing switch by which one of the sending outfits 95 may be appropriated to the use of that connecting circuit in establishing a connection, and means are provided whereby, during the use of the sender so taken, another sender 100

may be automatically made available to be seized by any other connecting circuit of that group which may be put into service before the first sender has finished its work.

- 5 More specifically, in the particular form of our invention at present contemplated, an automatic transfer switch is associated with the sender-seizing switch and determines which of the sets of sending apparatus shall
 10 be connected to the terminals of said seizing switch. Normally, one set of sending apparatus will be available for the seizing-switches of all the connecting circuits of the group, but upon the operation of any such
 15 seizing switch, the transfer-switches of all the other connecting circuits will be actuated to bring another set of sending apparatus into operative relation to the remaining seizing switches, while locking out said seizing switches from the busy set. When the first sender has finished its work it is automatically freed from the connecting circuit with which it has been operating, and is again made available to be seized by any
 20 other connecting circuit of the group.
 25

We will describe our invention more particularly by reference to the accompanying drawings representing the application of our invention to a mechanical telephone system, reserving, however, for the appended claims, a statement of the parts, improvements and combinations which we regard as novel with us.

In the drawings,

- 30 Figs. 1, 2, 3, 4, 5, 6 and 7 represent diagrammatically a calling and a called subscriber's line, with two operators' connecting circuits and two sending mechanisms, together with the mechanical switching mechanism associated with one of said connecting circuits.

These sheets of drawings, if placed edge to edge in the order of Figs. 7, 6, 5, 1, 2, 3, and 4 form a single diagram, the lines which are extended to the edge of each sheet being continued on the succeeding sheet.

We will first describe the circuits and apparatus which we have provided for enabling a connecting circuit to pick up an idle sending apparatus mechanism.

- 50 Fig. 1 shows two connecting circuits or cord circuits I and II of the group which is to be handled by a given operator, also shows the two sets of sender leads or wires extending from the primary and subsidiary senders. The complete mechanism of the primary sending apparatus is shown in Figs. 5, 6 and 7, but only a portion of the apparatus of the subsidiary senders is indicated, to avoid needless duplication. For brevity, we may hereafter refer to the primary and subsidiary senders as sender "A" and sender "B", respectively, but these letters are not used as reference-characters on the drawings.

Each connecting circuit has associated with it a sender-seizing relay 31, which is adapted when excited to interrupt the continuity of the connecting conductors 8 and 9 and to connect the extensions thereof to a pair of leads from one of the sending outfits,—the particular sender thus seized being determined by a transfer relay 21 also associated with each connecting circuit. Thus the leads 41 and 44 of the primary sender are normally connected through wires 505 and 506 through back contact of the transfer relay to armatures 492 and 493 thereof and by wires 502 and 504 to the armatures 39 and 40 respectively of the sender-seizing relay, which when attracted engage springs 42 and 45,—and thus extend the circuit to the connecting wires 8 and 9. The leads 41^a and 44^a of the subsidiary sender are connected to front contacts of the armatures 492 and 493 of the transfer relay, so that when said transfer-relay is excited, the armatures or terminals 39 and 40 of the sender-seizing relay are connected to said subsidiary leads 41^a and 44^a instead of the primary leads 41 and 44.

Each operator's connecting circuit is provided with a key 19 for tying a sending keyboard to such circuit. The contact spring 20 of each connecting circuit key, whose normally-open contact anvil is connected by conductor 22 to the free pole of battery 58, is connected with a conductor 28, which leads through armature 29 and back contact of relay 30, winding of relay 31, armature 491, and back contact of relay 21 to the common wire 495, which leads to the sending keyboard A, said conductor passing through the winding of a controlling relay 26 of said keyboard, through the armature 32 and back contact of a relay 33 to earth.

The front contact of armature 491 of relay 21 of each connecting circuit is connected with a conductor 496, which leads to the common wire 495^a extending to the keyboard B, and there passing through the controlling relay 26 of said keyboard to earth. Thus when armature 491 of relay 21 of either cord circuit rests against its back contact, the operation of spring 20 of key 19 of such connecting circuit will cause the operation of the controlling relay 26 of the A board, completing for said relay a circuit 22, 28, 495, including battery 58; while if the armature 491 of relay 21 of either connecting circuit is in engagement with its front contact, and key 19 of such connecting circuit be operated, a circuit 22, 28, 496, 495^a will be completed for the controlling relay 26 of the B board.

The relay 31 in the circuit of the controlling relay 26 of the sending apparatus taken for use is adapted when energized to complete a locking circuit for itself and

relay 26 independently of key 19 from battery 17, in the circuit 18, 35, 495 (or 495^a according to the keyboard secured) said locking circuit remaining intact until the 5 selected board has completed its work.

The relay 21 of each connecting circuit is provided with a winding 497 included in a conductor 499, leading from the back contact of armature 500 of relay 31, (which 10 armature is connected with the free pole of a battery 59) through the armature 24 and front contact of the controlling relay 26 of the A board to earth. Thus when 15 said armature 24 of the controlling relay 26 is attracted, due to the operation of a key 19 at one connecting circuit to associate keyboard A therewith, a circuit 499 will be completed at the other connecting circuit or circuits, including the winding 497 20 of relay 21, which will thereupon attract its armatures, armature 491 causing the controlling relay 26 of keyboard B to be operated when the key of such other connecting circuit shall be subsequently actuated, such circuit being by way of conductors 22, 28, 496, 495^a as previously described. The winding 498 of relay 21 of 25 each connecting circuit is included in a conductor 501 which leads from the front contact of armature 500 of relay 31, armature 494 and front contact of relay 21, winding 498 of said relay 21, to earth, so that when the relay 21 of an idle connecting circuit has been operated, as before 30 described, to bring the keyboard B into position to serve such connecting circuit, and the key 19 of such connecting circuit is subsequently operated to energize relay 31, a locking circuit will be completed for 35 relay 21 from the free pole of the grounded battery 59, conductor 501, winding 498, of relay 21, to earth, said locking circuit remaining intact until the keyboard B has 40 finished its work, in order to insure the continued association of keyboard B with such other connecting circuit, regardless of 45 the condition of the board A.

The relay 21 of each connecting-circuit is provided with armatures 492, 493, connected by conductors 502, 504 with the armatures 39, 40, respectively, of relay 31, said armatures 39, 40 being adapted when energized to separate two sets of springs 42, 43 and 45, 46, respectively, included in the 50 link conductors 8, 9, said armatures 39, 40, engaging springs 42, 45, respectively, which are directly connected with the portion of the strands 8, 9 leading to the switching mechanism. The back contacts of armatures 492, 493 are normally connected by conductors 505, 506, respectively, with local wires 41, 44 leading to the A board, and when said relay 21 of a connecting-circuit 55 is operated, while the other connecting-circuit is using selector-controlling mechanism

A, the armatures 492, 493 of said relay will be connected with conductors 507, 508 leading to local wires 41^a, 44^a, of the "B" board.

At the keyboard A, a branch conductor 38 leads from the feed wire 48 through the pilot lamp 509 to earth, and when the controlling relay 26 is operated during the use of the sending apparatus A, a circuit is completed for lamp 509, said lamp remaining illuminated during the use of the 70 sending apparatus. Similarly, at the keyboard "B" a pilot lamp 509 is provided in a circuit closed by the controlling relay 26 of said board, when operated.

To summarize, in case the connecting-circuit I is taken for use, and both keyboards "A", "B", are idle, the operator, observing the inert condition of both signal lamps 509 of the keyboards, will operate the keyboard "A", and upon the depression of key 19, such keyboard "A" will be tied to the cord circuit I by the locking circuit 18, 35, 37, 495, including the controlling relay 26 of keyboard A. The remaining connecting circuits will thereupon be transferred to the keyboard B, a circuit being completed by the controlling relay 26 of the A board, from the free pole of grounded battery 59 at connecting circuit II, by way of conductor 499, winding 497 of relay 21 of the idle connecting circuit, to earth through the armature 24 and back contact of relay 26 of keyboard A. This circuit will not be completed, however, at the cord circuit I because the armature 500 of relay 31 is attracted, removing battery 59 from the battery feed wire 499 of such connecting circuit. The circuit just traced includes winding 497 of relay 21 of connecting circuit II, which relay thereupon transfers at its armature 491 and front contact the key 19 of such connecting circuit to the control of the circuit leading to keyboard B, so that when said second connecting circuit is taken for use and the operator depresses key 19 of such circuit, the controlling relay 26 of the B board will be operated in the circuit 22, 28, 496, 495^a, which includes also the relay 31 of such connecting circuit, relay 31 in attracting its armature 500 completing a local locking circuit 501, including winding 498 of relay 21, armature 494 and front contact of said relay, and armature 500 and front contact of relay 31, so that in case the A board should complete its work prior to the complete 90 operation of the B board, and the initial circuit including winding 497 of relay 21 be broken by controlling relay 26 of the A board, the locking circuit 501 will maintain such relay 21 energized until the B board completes its work, whereupon said locking circuit is broken. It will be understood that while the keyboard A is in use, the lamp 509 will be displayed and the operator will know that keyboard B is the one 95

100

105

110

115

120

125

130

that will be tied to the cord circuit II when the key 19 thereof is operated.

We will now describe the complete system with which we have chosen to illustrate the application of our invention, and will first give a general outline of the mode of operation of such system.

In a system of, for example, 100,000 lines, there may be provided ten offices, at each of which terminates 10,000 lines. At each office the lines may be arranged in groups of 300, although groups of any number might be employed. With such an arrangement there would be approximately 34 groups of 300 lines at each office or, to be exact, 33 groups of 300 lines and 1 group of 100. Each connector has a capacity of 300 lines and enough connectors are furnished to handle the calls for each group. 10 The operator in an exchange answers a call in the usual way by uniting her connecting circuit with the line of the calling subscriber, and after ascertaining the number of the called party and the exchange where the line of such party terminates, 15 operates the idle sending apparatus, automatically assigned to her connecting circuit, depressing the key thereof, which represents the desired office, and the thousands, hundreds, tens and units digit keys representing the number of the line wanted. An office selector forms the terminals of the connecting circuit referred to, and is operated by mechanism controlled by the actuated office 20 key to unite the connecting circuit with an idle trunk line leading to the desired office. Said trunk line terminates at the desired office in a primary selector, which is a machine adapted to select an idle connector belonging to any one of the thirty-four groups.

A translator is provided in connection with the sending outfit to cause the thousands and hundreds keys depressed to operate the primary selector and pick out an idle connector of the group desired. The first 300 lines in the exchange are numbered 0000 to 0299. These numbers would be reached by pressing the "naught" button of the thousands keys and the "1" or "2" button of the hundreds keys. There is a primary controller at the sending outfit which controls the operation of the primary selector, the two being operated together in series. The 25 translator is provided with three brushes. The first is associated with the thousands and hundreds keys and arranged to stop the translator at a predetermined point to cause the second brush and the primary controller which are automatically brought into circuit when the translator has stopped, to advance the primary selector into position to connect with the desired connector. The third brush has associated therewith an auxiliary controller; and said brush after the operation

of the primary controller automatically brings into play the auxiliary controller which advances the brushes of the selected connector to the proper hundreds zone of the three zones of one hundred lines each of such connector. The depressed tens and units keys are now brought successively into service, the mechanism controlled thereby operating the selected connector to cause the brushes thereof to unite with the terminals of the desired line in the selected zone. 70

We will now describe in detail the circuits and apparatus employed in connecting the subscriber shown in Fig. 1, whose line terminates at office "C", with the line of the subscriber No. 1132 shown in Fig. 4, whose line terminates at exchange "D", using the connecting circuit I.

The line of subscriber 999, Fig. 1 extends in two limbs 1, 2, from the substation to 85 the central office "C" where the line extends through the usual line signal apparatus to the poles of a central battery. At the central office, the usual answering jack 3 is provided for the line, the thimble 4 of said jack being connected with a conductor 5 which leads through the usual cut-off relay to the free pole of a grounded battery 6. The operator is provided with an answering plug 7, with which to unite her connecting 90 circuit with the calling line, the plug 7 and jack 3 constituting a manual connection switch.

The link conductors 8, 9 of the operator's connecting circuit lead from the tip 16 and 100 ring 11, respectively, of the answering plug, through the windings of the usual repeating coil between which is bridged a battery 12 in the usual manner, to the line brushes of an office selector 13, Fig. 2, a supervisory relay 105 being included in link-conductor 9 between the battery and the ring of the plug for controlling the usual supervisory signal. The sleeve 14 of the answering plug is connected with a conductor 15, which leads to 110 earth through the winding of a relay 16. Said relay 16, whose circuit 5, 15 is completed upon the closure of the connection switch, is provided with an armature connected with the free pole of the battery 17, 115 the front contact of said armature being connected with a conductor 18 leading through contacts of the supervisory relays and the supervisory lamps to earth.

A key 19 is provided in association with the conductors 8, 9 of the connecting circuit, adapted, when operated, to unite the operator's telephone set with the link conductors of the connecting circuit, and also to close a pair of contacts, which control the placing of an idle one of the sending keyboards A B into condition to serve said connecting circuit. The anvil of spring 20 is connected with a conductor 22 which leads to the free pole of a grounded battery 58, 120

while the spring 20 is connected with a conductor 28 which leads through the armature 29 and back contact of relay 30, windings of relays 31 and 26, armature 32 and back contact of relay 33 to earth. Thus when key 19 of connecting circuit I is operated, relay 31 thereof is energized, as well as the controlling relay 26 of the idle sending apparatus, in the present case, keyboard A.

Referring first to relay 31, its armature 34 is connected with a conductor 35 which leads through the contacts of a key 36 to conductor 18, said conductor 18 being connected by the armature of relay 16 with the free pole of battery 17. The front contact of the armature 34 of relay 31 is connected with a conductor 37 which leads through the winding 38 of relay 30 to the armature 29 thereof. A locking circuit is now completed for the relays 26 and 31 independent of battery 58, said circuit extending from the free pole of battery 17 by way of conductors 18 and 35, armature 34 and front contact of relay 31, winding 38 of relay 30 to conductors 28, 495 and thence through the winding of relay 26 of board A to earth. The armature 29 of relay 30 is now operated and disconnects the key 19 from the circuit of the magnets 31, 26, so that the operator may at any time hereafter during the process of establishing the connection, or during the connection, listen in on the circuit without interfering with the sending apparatus. The resistance 23 is for the purpose of preventing a short circuit of the relay 30 when the armature 34 of relay 31 closes the branch through winding 38 of relay 30 from battery 17.

The relay 31 is also provided with armatures 39, 40. The armature 39 is united with a conductor 502, normally connected with wire 41, leading to the sending apparatus A, and said armature is adapted when attracted to engage the member 42 of a pair of normally closed springs 42, 43, included in the strand 8 of the connecting circuit, to separate said springs, the spring 42 being connected with the portion of the conductor 8 leading to the office selector. In like manner, the armature 40 is connected with a conductor 504 normally connected with a common wire 44 leading to the sending apparatus, A, said armature being adapted to engage the member 45 of a pair of springs 45, 46, which are normally included in the ring strand 9 of the connecting circuit, to separate said springs, the spring 45 being connected with the portion of the strand 9 leading to the office selector. Armatures 39, 40, therefore, in their attractive movement, connect the strands 8, 9 of the connecting circuit with the common wires leading to an idle sending apparatus. The armature 500 in its attractive movement removes battery 59 from wire 499 leading through relay 499.

The relay 26 of board A (Fig. 5) in operating, attracts its armature 47 which is connected with the free pole of grounded battery 27, said armature being provided with a front contact connected with feed 70 wire 48 leading to the mechanism of the sending apparatus. The retaining magnets of the sending apparatus are permanently connected with the feed wire 48, and are operated the instant battery is applied by 75 armature 47 of relay 26 to the feed wire. The lamp signal 509 is also connected to earth, from the feed wire, and remains displayed while the sending apparatus is in use. The sending apparatus A is now in 80 operative condition to serve the connecting circuit. The relay 26 of board A also brings about the switching of the remaining connecting circuits to the B keyboard, said relay 26 completing at its armature 24 and front contact, a circuit 499 associated with connecting circuit II, through the winding 497 of relay 21 of said second connecting circuit, whereupon said relay 21 switches the local circuits of the connecting circuit 90 II to the keyboard "B".

Operation of the office selector.

The office selector (Fig. 2) is provided with a shaft 50 arranged to have two movements—a rotary movement to select a group of trunk lines leading to a particular office, or as in the present case a group of trunk lines leading to trunk selectors adapted to select an idle inter-office trunk, and a longitudinal or upward movement to select the first idle trunk line of such group. This shaft carries three brushes 51, 52, 53, brushes 51 and 52 being connected with the strands 8, 9 of the connecting circuit, and the brush 53 being the local brush. The shaft 50 is adapted to be rotated by means of the magnet 54 and mechanism controlled thereby, and to be moved upward by a magnet 55 and its associated apparatus. The relay 30 (Fig. 1) when operated, as before described, serves to place the office selector in condition for operation. The armature 56 of relay 30 is connected with the conductor 57, which leads from conductor 35 and battery 17 through a winding of relay 30, armature 56 and its front contact, to the office selector, and thence through the winding of a relay 61 and through a pair of contacts 62 closed by the shaft 50 when in normal position, to earth. A circuit for relay 61 is thereby provided by conductors 18, 35, 57. The said relay 61 when energized attracts its armatures 63, 64 and 65 the armature 63 being connected with earth, and when attracted completing a locking circuit for the relay 61 independent of contacts 62. The armature 65 is connected with the free pole of a grounded battery 67, said armature when attracted engaging its front contact 130

- which is connected with a conductor 68 leading to earth through the winding of the retaining magnet 66 of the shaft 50. The armature 64 of said relay is connected with the free pole of battery 67 and the front contact of this armature is connected with a conductor 69 which leads through the contact springs 70, 71, associated with relay 72, through the winding of relay 73 to earth.
- 10 Relay 73 is provided with two armatures 74, 75, which with their back contacts are normally included in the strands 8, 9 of the connecting circuit, the armatures being connected directly with a portion of the strands leading to the plug 7. The armature 74 is adapted when attracted to engage a front contact which is connected with the conductor 76 leading through the rotary stepping magnet 54 of the shaft 50, through the contact springs 77, 78, associated with relay 72, to earth.
- 15 The armature 75 of relay 73 when attracted is adapted to engage a front contact connected with a conductor 79 which leads through the armature and front contact of retaining magnet 66, relay 72, to earth. The office selector is now in condition for operation.
- 20 Turning now to the sending apparatus A, we will describe the means adapted to be set by the operator to actuate the office selector and select an idle trunk line leading to the exchange where the called party's line terminates. In the present case the selector selects a trunk line which leads to an idle trunk selector, said selector thereupon operating to pick out an idle trunk line leading to the desired office. We will assume that the line of the party with whom conversation is desired terminates at office D, and that his number at said office is 1132. The operator, therefore, after listening in to ascertain the line desired and after ascertaining by the condition of lamps 509, which sending apparatus has been associated with her connecting circuit I, in the present case, keyboard A, depresses office key D, key I of the thousands keys, key I of the hundreds keys, key III of the tens keys, and key II of the units keys.
- 25 The office controller (Fig. 7) is provided with a series of keys C, D etc., which are known as the office keys. Each key comprises a plunger adapted when depressed to be locked in such position under the control of a release magnet 80. Each plunger may carry a latch member, preferably conical in form, adapted when the plunger is depressed, to engage the under side of a latch bar to lock the plunger in its depressed position, said plunger, when the latch bar is operated by magnet 80, being restored by a suitable spring. Each of said keys, when depressed, forces into electrical contact springs 82, 83, 84. The

spring 82 of each key is connected with the feed wire 48 previously referred to, which is connected by relay 26 with the free pole of battery 27. The spring 83 is connected with the conductor 85 which leads to a terminal of a bank of contacts 86 adapted to be engaged by the contact arm 87. Said arm is provided with a stepping magnet 88, the retaining magnet 89 of said contact arm being operated by current from the feed wire 48, as previously described. Said contact arm 87 is connected with a conductor 90 which leads to earth through the winding 92 of relay 91.

The third spring 84 of each key is connected with a conductor 93 which leads through the winding of relay 94, springs 95, 96, associated therewith, to the ground contact of a pulsator 97, said contact being arranged to be intermittently engaged by the grounded spring 98 of said pulsator. The spring 99 of said pulsator is connected with the free pole of grounded battery 100, the contact of said battery spring being connected with a conductor 101 leading to the armature 102 of relay 94. The front contact of said armature 102 is connected with a conductor 103 which leads through the winding of the stepping magnet 88 of contact arm 87, armature 104 and back contact of relay 91, through the armature 105 and back contact of sluggish relay 106 to common wire 41.

Assume now that key D has been operated: Current will flow from the feed wire 48 by way of springs 82, 83, to the contact 86^a in the bank 86. Battery will also be applied from the feed wire through the springs 82, 83, 84, to conductor 93, and thence through winding of relay 94, springs 95, 96, of said relay to earth by way of the pulsator when spring 98 thereof engages its contact. When such contact is made, relay 94 is energized to attract its armatures 102, 107. Armature 107 is connected to earth and engages contact spring 95, separating the same from its anvil 96 and completing a locking circuit for relay 94 from the feed wire independent of the pulsator. Armature 102 in its attracted position connects the battery contact of the pulsator with conductors 101, 103. Impulses of current now flow from the free pole of battery 100 over conductors 101, 103, winding of the stepping magnet 88 of contact arm 87, over common wire 41, conductor 502, through armature 39 and spring 42 of relay 31 (Fig. 1) to the tip-strand 8, armature 74 of relay 73 of the office selector (Fig. 2), conductor 76, through the stepping magnet 54 of the selector, springs 77, 78 of relay 72 to earth.

The pulsator 97, as already described, when in position to close its grounded contact completes a circuit for the relay 94

which connects the battery contact of the pulsator to the stepping magnets. This provision is made so that the first impulse applied to the stepping magnets will be a 5 full one, that is, when the pulsator is engaging its ground contact it completes the circuit for relay 94, so that when it engages its battery contact the circuit for the stepping magnet will be ready to receive 10 the complete impulse.

The stepping magnets 88, 54, respond together to the pulsating current and rotate the contact arm 87 of the controller and the shaft 50 of the selector, respectively. When 15 the contact arm 87 of the office controller reaches the contact point 86^a, which is connected through the key 0 with the feed wire, and the shaft 50 has been stepped around so as to bring its brushes in front 20 of the group of terminals leading to trunk selectors adapted to pick out idle trunk lines leading to the desired office, current flows from the feed wire through the contact springs 82, 83, conductor 85, contact 86^a, 25 of the bank 86, contact-arm 87, conductor 90, through the winding 92 of relay 91 to earth. Relay 91 is thereby energized and attracts its armature 104, removing pulsating current from the stepping magnets 30 88, 54. The armature 108 of relay 91 is connected to earth while its front contact is connected with a conductor 109 which leads through the winding 110 of relay 91, winding of sluggish relay 106, to the feed 35 wire. The armature 108, therefore, when attracted completes a locking circuit for relay 91, and also the circuit of the sluggish relay 106.

40 *Automatic selection by selector of trunk line.*

A conductor 111 extends from conductor 90 between the arm 87 and relay 91 to the back contact of armature 112 of sluggish 45 relay 106, said armature 112 being connected with common wire 44, and when the arm 87 reaches the point 86^a at which battery is present, an impulse is delivered before the relay 106 has had time to operate, to conductor 44 by way of conductors 85, 90 and 50 111 and the armature 112 and back contact of relay 106. This impulse passes through the armature 40 and its contact 45 of relay 31, (Fig. 1) strand 9 of the connecting 55 circuit to the office selector, thence through the armature 75 and its front contact of relay 73, conductor 79, armature and front contact of retaining magnet 66, winding of relay 72 to earth. Relay 72 is thereupon 60 operated and attracts its armatures 113, 114, 115. The armature 114 is connected with conductor 79, and is adapted when attracted to engage a contact connected with the conductor 69 which leads to the free pole of 65 battery 67, thereby completing a locking

circuit for the relay 72 from the free pole of battery 67, armature 64 of relay 61, conductor 69 to earth by way of armature 114 and conductor 79.

The armature 113 of relay 72 is connected with a conductor 116 which leads to the front contact of armature 117 of relay 73, said armature 117 being connected with a conductor 118 leading to the local brush 53 of the shaft 50. Said armature 113 when 70 attracted engages the spring 71 connected directly to earth through relay 73, and connects said relay through its own armature 117 and front contact with the local brush 53, for a purpose to be later explained.

The armature 115 of relay 72 when attracted engages contact spring 78, thereby opening the branch 76 containing the stepping magnet 54. Said armature is connected with a conductor 119 which leads through the lifting magnet of the selector, armature 120 and front contact of relay 73 to the battery contact of a pulsator 121. The shaft 50 now begins its upward hunt for a trunk line leading to a idle selector adapted to pick out an idle trunk line leading to the office B. If the first trunk line is busy, battery will be present upon its local terminal 122, and will maintain relay 73 excited in the path provided by way of conductor 118, armature 117 of said relay and its front contact, conductor 116, armature 113, and front contact of relay 72, conductor 69, to earth; the armature 120 of said relay 73 while attracted maintains the circuit of the stepping magnet 55.

When, however, an idle trunk line is reached by the brushes on the shaft 50, there will be no potential present at the local terminal 122 thereof and the relay 73 will 105 be deprived of current, and will release all its armatures, armature 120 opening the circuit of the lifting magnet 55; armatures 74, 75 restoring the continuity of the strands 8, 9 of the connecting circuit; and the armature 117 breaking the connection of relay 73 with the local brush 53 and connecting at its back contact conductor 118 leading from said brush with a conductor 123 leading to conductor 69, which is connected by armature 64 of relay 61 with the free pole of battery 67. The brushes 51, 52, 53 of shaft 50, now rest in engagement with contact terminals 124, 125, 122, respectively, connected with a trunk line, leading to a trunk 110 selector.

Operation of trunk selector.

The trunk selector comprises a shaft 126 having one movement, a rotary movement, 125 said shaft being provided with a stepping magnet 127. The shaft carries three brushes 128, 129, 130; the brushes 128, 129 being line brushes connected by conductors 131, 132, with the contact terminals 124, 125 130

of the office selector, the armatures 133, 134, and back contacts of a relay 135 being included in said conductors 131, 132, respectively. The local trunk terminal 122 of the selector is connected with the conductor 137 which leads through the retaining magnet 138 of the trunk selector, contacts 139 closed by the selector shaft 126 when in normal position, winding 140 of relay 135 to earth, current being delivered to said conductor 137 from battery 67, when the brush 53 engages said contact 122 and the relay 73 has restored its armature, as previously described, whereupon relay 135 and retaining magnet 138 are operated.

The retaining magnet 138 in operating attracts its armature and completes a locking circuit for itself independent of contacts 139 through its own armature, resistance 138^a and ground, the function of this resistance being to prevent the short-circuiting of relay 135. Relay 135 in operating attracts its armatures 133, 134, 141 and 147. The armatures 133, 134 when attracted maintain the selector brushes 128, 129 dead during selection. The armature 141 is connected with a conductor 142 which leads through the winding 143 of relay 135 to earth. Said armature 141 in its attracted position engages the contact spring 144, and separates the same from its normal contact 145, said spring 144 being connected with a conductor 146 leading to the local brush 130. The armature 147 is connected with a conductor 148 which leads to the battery contact of the pulsator 149, while the front contact of said armature is connected with conductor 150 leading through the winding of the stepping magnet 127 of the trunk selector to earth.

Thus when relay 135 is attracted, a circuit is completed by armature 147 by way of conductors 148—150, said circuit including the magnet 127, which is operated to advance the test brush 130 on shaft 126 one step to the terminals of a trunk line leading to the desired office. If this trunk line is busy, battery will be present at the local terminal 151 of such line, and current will flow through the local brush 130, conductor 146, spring 144 and armature 141, conductor 142, winding 143 of relay 135 to earth, maintaining the relay 135 energized. The stepping magnet 127 will thus continue to receive current and will advance the shaft another step, and so on until an idle trunk line is found, whereupon current will not be present upon the terminal 151, and relay 135 will be deprived of current, releasing its armatures and restoring the continuity of the talking conductors 131, 132, which were broken during selection to prevent disturbances; opening at armature 147 the circuit of the stepping magnet 127; and breaking at armature 141 the connection of relay

135 with the local brush 130. Spring 145, which now rests in engagement with spring 144, is connected with a conductor 152 leading to conductor 137, which is connected with battery 67 at the office selector, and a potential is thereby applied by way of conductors 69, 123, 118, 137, 152, 146 to the contact terminal 151 of the trunk line upon which the selector brush 130 rests, to lock out other trunk selectors from the trunk line selected. The brushes 128, 129 of the trunk selector now rest upon the terminals of the limbs 152, 153, respectively, of a two-wire trunk line leading to the office D and the primary selector forming the terminal of such trunk line at said distant office.

Operation of translating machine and primary selector.

As before stated, the line with which connection is desired, is numbered 1132. Therefore the operator depresses key I of the 1000's keys 154, key I of the 100's keys 155, key III of the 10's keys 156, and key II of the units keys 157. The 1000's and 100's keys control the operation of the translator shown at the left in (Fig. 6) which operates the primary selector 136 (Fig. 3), forming the terminal of the trunk line at the distant office, to connect the trunk lines with an idle connector of the group containing the desired number. The shaft 159 of the translator is arranged to have two movements, one in long steps under the control of stepping magnet 160, and the other in short steps under the control of magnet 161. The shaft carries three brushes, the brush 162 being adapted to co-operate with the depressed 1000's and 100's keys, and the bank of contacts 163 to stop the shaft at the proper point to cause the brush 164 of the translator to apply battery to a particular contact of the primary controller 165, and cause the same to operate in series with the primary selector until the contact arm 166 of the primary controller reaches the contact to which battery has been applied by brush 164 and the primary selector reaches the group of trunks leading to the connectors of the group wherein is located the called party's line, at which time the primary controller and primary selector are stopped, and the primary selector caused to locate an idle connector. The third brush 167 of the translator is provided with a bank of contacts 168 which control the application of battery to a pre-determined point upon the auxiliary controller 169, which is operated after the primary selector has located the connector to advance the brushes of such connector into the proper bank of its three banks of 100 lines each.

Describing now more in detail the operation of the translating mechanism and primary selector. The relays 511 and 172 (Fig. 130

7) control the starting of the translating mechanism, said relays being arranged to operate when the trunk selector has made connection with an idle trunk line leading 5 to a distant office. Said relay 511 is included in a conductor 170 leading from the front contact of the armature 105 of the relay 106, through contact springs 171 controlled by the armature 173 of relay 172, to the 10 feed wire 48, the connection of this conductor at armature 105 of relay 106 with wire 41 being completed when the sluggish relay 106 is operated after the impulse is applied to wire 44 to start the office selector in its 15 upward hunt for an idle trunk selector. The circuit for relay 511 extends from the feed wire 48 through the conductor 170 to conductor 41, thence through contacts 39, 42 of relay 31, to link conductor 8, over trunk 20 wire 131 to the trunk selector, through the contacts closed thereby, to trunk wire 152 leading to the distant office, where the same passes through one winding of a repeating coil bridged across the trunk conductors to 25 a conductor 174, which leads through the winding of relay 175, normally closed contacts 176, 177 of a polarized relay 178, normally closed contacts 179, 180 of said relay, 30 normally closed contacts 181, 182 of relay 183, to trunk conductor 153, and thence to the primary selector, through the armature 184, and back contact of relay 185, to a conductor 186, which leads through contact springs 187 closed by the shaft of the selector 35 while in normal position, to earth. The relays 511 and 172 of the sending apparatus (Fig. 7) are sluggish in their operation to provide a time interval wherein the primary selector may get into condition for 40 operation. This is accomplished under the control of the relay 175 associated with the trunk line at the distant office, which is in the circuit just traced for the relay 511. Said relay 175 in attracting its armature, 45 completes a circuit from battery 189 by way of conductor 190, which leads through the normally closed contact springs 191, 192 of relay 193, winding of relay 193, winding of the retaining magnet 194 of the primary selector, to earth, through the contact springs 50 closed by the shaft 195 of the primary selector when in normal condition. The relay 193 and retaining magnet 194 are now energized and a locking circuit is completed 55 for said relay and magnet independent of relay 175, said circuit extending from the free pole of grounded battery 196, conductor 188, through the contact springs 197, 198, of relay 183, armature 199 of relay 193, 60 (which is now in engagement with the contact spring 191, separating the same from its normal contact 192, and disconnecting battery 189 from the circuit previously traced) through the winding of relay 193, 65 and over conductor 190, through the wind- ing of the retaining magnet and its armature 200 and front contact to earth. The armature 201 of relay 193, which is connected with the portion of conductor 190 leading to the front contact of the armature of relay 175, in its attracted position opens the contact springs 202 which are normally included in the trunk conductor 152, and engages the member thereof which is connected with the portion of the trunk conductor 70 152, leading directly to the primary selector, the contacts 202 being included in said conductor between the repeating coil and the selector. 75

The repeating coil serves to maintain the inductive continuity of the trunk circuit while maintaining the circuit broken for direct current. The two windings of the repeating coil connected with the portion of the trunk circuit leading back to the trunk 80 selector are included in a bridge of said trunk conductor with a condenser, while the other two windings of the repeating coil, which are included in the portion of the trunk circuit leading to the selector, are included in a bridge of the trunk circuit with a grounded battery 203. 85 90

The retaining magnet 194 when energized as previously described, attracts its armature 204, completing a circuit from battery 95 205 by way of conductor 206, through the contact springs 207, 208 of relay 209, winding of relay 185 to earth, said relay thereupon attracting its armatures 210, 184, 211 and 212. 100

The armature 210 of relay 185 which with its back contact is normally included in the trunk conductor 152, when attracted engages a front contact connected with the conductor 213 leading through a stepping 105 magnet 214 of the primary selector, contact springs 215 of relay 209 to earth. The magnet 214 is arranged to rotate the shaft 195 in thirty-four steps to pick out the group of trunk lines leading to connectors serving a 110 particular group of 300 lines. The remaining armatures of the relay 185 bring into operative condition apparatus which will be hereinafter described. 115

The primary selector is now in condition for operation, and sluggish relay 511 of the sending apparatus (Fig. 7) has now operated to operate relay 172, which in turn causes the deenergization of relay 511, said relay 172 locking itself up, and the combination of relays 511 and 172 with the first-mentioned relay inert and the other energized, starts the translating mechanism. Relay 511 is provided with an armature 120 216 connected with the feed wire 48, said armature when attracted, completing a circuit for the relay 172, armature 173, opening the contacts 171 which are included in the circuit of the relay 511, and by means of said armature 173 and one of the members of 125 130

the contacts 171, said relay 172 is locked to earth from the feed wire. The armature 216 of relay 511, which is connected with the feed wire, is provided with a back contact connected with a conductor 217 leading through the armature 218 and its front contact of relay 172 to the 1000's keys, and when armature 216 of relay 511 is retracted, and armature 218 of relay 172 is attracted, 10 current flows from the feed wire over conductor 217 through the armature 219 and back contact of relay 220 to the 1000's keys 154. (Fig. 6).

Each 1000's key, when operated, is arranged 15 to be locked in its depressed position under the control of a release magnet 221, as described in connection with the office controller; each key when depressed forcing into electrical engagement contact springs 222, 223 and 224. Contact spring 222 is connected with the conductor 217, which is united by the feed wire 48 to the free pole of battery 27, and said spring in engaging its anvil 223 applies battery to a thousands 20 contact terminal in the bank 163 over which the brush 162 of the translator sweeps. In the present case—calling line 1132—since key I is depressed, battery will be applied to the second thousands contact point 225 25 of the bank 163. It will be understood that the brush 162 normally rests one long step from the first terminal which would be "0" or the first thousands terminal. In the system shown, in order that the brush 162 may 30 reach the second thousands contact point 225, it is arranged to take three long steps. Between the first and second thousands contact points there are ten intermediate contacts numbered from "0" to 9 inclusive; and the advance of the brush to any of said 35 intermediate contacts is determined by the 100's keys.

The spring 224 of key I, which is now in 40 electrical engagement with springs 223, 222, and thereby with battery 27, is connected with a conductor 226 which extends from all the springs 224 of the 1000's keys, through the winding of relay 227, contact springs 228 associated therewith, to the 45 ground contact of a pulsator 229; and when the ground spring of the pulsator engages said contact a circuit is completed for relay 227 which draws up its grounded armature 230, said armature engaging the member of spring 228 connected with the winding of 50 relay 227 and completing a locking circuit for said relay independent of the pulsator.

The relay 227 is arranged to start the 55 operation of stepping magnet 160 of the translator, said relay having an armature 231, which, when attracted, completes the continuity of a conductor 232 leading from the battery contact of a pulsator 233, through the winding of relay 234, armature 235 and

back contact of relay 236 to the conductor 65 41, which is connected with the tip strand of the connecting circuit and on through to the primary selector. It will be noted that the locking circuit for relay 227 is established by the pulsator 229 when in engagement with its ground circuit so that the circuit of conductor 232 will be completed before the pulsator 233 engages its battery contact, thus insuring a complete initial impulse over conductor 232. 75

When the battery spring of the pulsator 233 engages its contact, current flows over conductor 232 through the relay 234, over conductor 41, tip strand 8, trunk conductors 131, 152, through one winding of the 80 repeating coil to conductor 174, thence through relay 175, contacts of relays 178 and 183, through the armature 184 and front contact of relay 185, to conductor 237, through contacts 238 of relay 209 to earth 85 through the winding of said relay, this current being without effect upon said relay 209. Relay 175 in the circuit just traced responds to said current, and in attracting its armature applies current from battery 189 to conductor 190, and thence through armature 201 and one of the members of springs 202 of relay 193, to trunk conductor, 152, thence through armature 210 and its front contact of relay 185, conductor 213, rotary stepping magnet 214 of the primary selector, contact springs 215 of relay 209 to earth, whereupon the stepping magnet 214 is operated to rotate the shaft 195 one step. This advance of the primary selector is 90 simply to save time in the operation of the system. 95

The relay 234 in the circuit traced from the pulsator 233, responds to the pulsations and applies current from battery 239 100 through the armature 240 and its front contact of said relay 234, to the long step magnet 160 of the translator, which advances the contact arm of the translator in long steps. The relay 234 has an armature 110 241 also connected with battery 239, said armature when attracted applying current from said battery to a conductor 242, which leads to earth through the stepping magnet 243 of the primary controller 165, to advance 115 the arm 166 thereof.

It will thus be seen that the translator arm, the contact arm of the primary controller, and the contact arm of the primary selector, advance together until the brush 120 162 of the translator reaches the thousands point 225 of the bank 163 of contacts, at which time each of said arms will have taken three steps—the translator arm three long steps and the primary selector arms three 125 short steps each. The holding or retaining magnets of the translator and primary controller are permanently connected with the

feed wire 48, and were operated the instant relay 26 applied battery to the feed wire, when the sending apparatus was taken by the connecting circuit for use.

5 When the brush 162 of the translator reaches the contact 225 it finds current thereon, and said current passes through the brush 162 to a conductor 244, which leads through the armature 245 and back contact 10 of relay 220, through the winding 246 of relay 236, operating said relay 236, which opens at its armature 235 and back contact the conductor 232, and the circuit before traced, including the relay 234, pulsator 233, 15 and the relay 175 at the primary selector, so stopping the movement of the contact arms of the translator, primary controller and primary selector.

The translator is now ready to respond to 20 the control of the hundreds keys and seek the intermediate point beyond the contact 225 where it is desired to finally stop the translator arm. In the present case, since key I of the hundreds keys is depressed, 25 the second intermediate point beyond point 225 would be supplied with battery in the following manner:

Relay 236 when energized, as above described, attracts its armature 247, which is 30 connected with a conductor 248 leading through the relay 220 to the feed wire 48. The front contact of armature 247 is connected through a winding of relay 236 to earth; and when said armature 247 is attracted, a circuit is completed for the relay 35 220 which attracts its armatures 219, 245. Armature 219 when attracted connects conductor 217 and battery 27 with conductor 249 leading to the springs 250 of the hundreds 40 keys 155. The armature 245 of relay 220 in its attracted movement connects conductor 244 leading from brush 162 with a conductor 251 leading through the winding of the relay 252 to earth. Brush 162 is now 45 dead since battery is removed by armature 219 of relay 220 from the 1000's keys, and so from contact 225. The three springs of key I of the 100's keys are now in electrical connection (key I being locked in its depressed position under the control of a release magnet 428) and the middle spring 512 50 applies battery from spring 250 and conductors 249, 217 to the second intermediate contact beyond point 225. The third spring 55 253 applies current by way of the springs 250, 512 and conductors 249, 217, to conductor 254 leading through winding of relay 255, to earth; said relay 255 in attracting its armature completing the continuity of a 60 circuit 513, which extends from the battery contact of a pulsator 257, through the winding of the short-step magnet 161 of the translator, through the armature 258 and back contact of relay 252 to earth. The pulsator

257 applies current through the circuit just 65 traced to operate the stepping magnet 161 and advance the shaft in two short-steps, until the brush 162 of the translator rests upon the second intermediate point beyond a contact 225, at which time current will 70 flow by way of brush 162 and conductor 244 through the armature 245 and front contact of relay 220, conductor 251, to earth through relay 252, which will attract its armature 258 and open the circuit of the 75 pulsator 257 and the stepping magnet 161 of the translator, leaving the shaft of the translator three long steps and two short steps from its normal position.

Primary controller.

80

The primary controller in an exchange such as we are describing, where the lines are arranged in groups of three hundred, would have thirty-four contact points, each 85 point representing a "group" contact point of a primary selector, which in like manner would have thirty-four rotary steps to engage thirty-four terminals. From each terminal of the primary controller a conductor 90 runs to three contact points strapped together, over which the second brush 164 of the translator is arranged to sweep, said brush being adapted after the translator has been brought to a predetermined point under the control of the 1000's and 100's keys, to apply battery to a certain group of strap contacts to stop the controller and selector, when the selector is advanced to the group 95 of trunk lines leading to the connectors 100 serving the group of lines in which the called party's line is located. The operation of the primary controller and selector is automatically effected immediately upon the completion of the movement of the 105 translator. The relay 252 which was operated the instant the translator brush landed on the second intermediate point in attracting its armature 262 applied current from a positive battery 263 to conductor 264 leading to the brush 164 which now rests upon the set of strapped contacts connected with the fourth contact 265 in the bank of contacts of the primary controller 165.

It should be remembered at this point that 115 the primary controller and primary selector follow the long steps of the translator brush, so that the arm 166 of the primary controller and the brushes on the shaft 195 of the primary selector rest on their third 120 "group" terminals. This arrangement is simply to save time in setting up the connection.

The armature 266 of relay 252 which was 125 operated when the translator completed its movement, serves to start the primary controller and selector, said armature 266 being connected with a grounded contact of the

pulsator 267, the front contact of said armature being connected with a conductor 268 leading through contacts 269 of the relay 270 and winding of said relay to the feed 5 wire 48. The instant the ground spring of the pulsator 267 engages its contact, a circuit is completed from battery 27 over the feed wire 48, conductor 268, through relay 270, armature 266 and front contact of relay 252, to earth; and the relay 270 in operating attracts its armature 271 which separates springs 269, engaging one of such springs to complete a locking circuit of such relay 270 from the feed wire independent 10 of the pulsator.

An armature 272 is provided for relay 270 which is connected with the battery contact of a pulsator 273, the front contact of armature 272 being connected with a conductor 274 leading through a relay 275, armature 276 and back contact of relay 277, to conductor 41, which leads to the tip strand 8. Relay 275 controls a circuit from battery 278 through the stepping magnet 243 of the controller. The pulsator 273 applies current through the relay 275 and out over conductor 41, tip strand 8, trunk conductors 131, 152, to the distant office, and thence through conductor 174, relay 175, contacts 181, 182, of relay 183 to trunk conductor 153, thence through conductor 237, and relay 209, to earth, this current, however, not affecting the relay 209. The relay 175 responds to the impulses in the circuit traced, and completes a circuit from battery 189 over conductor 190, armature 201 of relay 193, and one of the springs 202 to the trunk conductor 152, and thence through the armature 210 of relay 185, conductor 213, stepping magnet 214 of the primary selector, contacts 215 of relay 209 to earth. The relay 275 associated with the primary controller and included in the circuit of pulsator 273 above traced, makes and breaks the circuit of the stepping magnet 243 of the controller. The stepping magnet 243 of the controller and 214 of the selector, now rotate their respective contact arms until the contact arm 166 of the controller reaches the fourth contact in its path, which is connected by the brush 164 and conductor 264 with positive grounded battery 263, at which point current flows from said battery through the arm 166 of the controller and the conductor 269 leading from said arm through a winding of relay 277 to earth. Relay 277 now operates and attracts its armature 276, opening the circuit from the pulsator 273 through the relay 275 of the primary controller and the relay 175 at the distant office, said relay 175 controlling the circuit through the stepping magnet 214 of the primary selector. Said relay 277 also draws up its armature 280, completing a locking circuit for itself,

which extends from the feed wire 48 through sluggish relay 281, winding of relay 277 to earth. The brushes on the shaft 195 of the selector have now reached the fourth group of trunk lines, which lead to connectors adapted to reach the line with which connection is desired. 70

Automatic selection of idle trunk by selector.

The attraction of armature 276^a of relay 277 completes the continuity of a conductor 282 which leads from the conductor 269 (Fig. 6) between the brush 166 and relay 277, through the armature 276^a and front contact of relay 277 armature 283 and back contact of sluggish relay 281, to conductor 44, and before the sluggish relay 281 has had time to operate, an impulse from positive battery 263 flows by way of conductor 264, brush 164, contact arm 166, and its fourth terminal, conductors 269 and 282, conductor 44, to the ring strand 9 of the connector circuit, trunk conductors 132, 153, through a lower winding of the repeating coil, to conductor 284, which leads through the contact springs 285, 286, winding of the polarized relay 178 to earth. Said positive current causes the relay 178 to tilt its armature in a contra-clockwise direction, whereupon spring 177 of said relay is separated from its anvil 176 and thrown into engagement with a contact 287 connected with the free pole of grounded battery 288; current thereupon flowing from battery 288 through the springs 287, 177, conductor 174, contacts 181, 182 of relay 183, trunk conductor 153, armature 184 and front contact of relay 185, conductor 287, springs 238 of relay 209, and winding of said relay to earth. 90

Relay 209 is now energized and draws up its armatures 289, 290, 291. The armature 290 is connected with conductor 206 which leads from the battery 205; and said armature when attracted separates springs 238, engaging the member thereof leading directly to earth through relay 209, and completing a locking circuit for said relay independent of relay 178, which by this time has been deprived of current owing to the operation of the sluggish relay 281. Armature 291 of relay 209 is connected with a conductor 292 leading through the lifting magnet 293 of the primary selector, armature 212 and front contact of relay 185 to the battery contact of a pulsator 294. And said armature 291 when attracted is adapted to separate springs 215, breaking the continuity of conductor 213 connecting the rotary stepping magnet 214 with trunk conductor 152, and to engage the grounded contact spring of said pair of springs 215 to complete a circuit for the lifting magnet 293 and the pulsator 294. Said magnet 293 is adapted to step the shaft 195 up in search of a trunk line leading to an idle connector 130

adapted to serve the fourth group of three hundred lines in which the line desired, number 1132 is to be found.

The armature 289 of relay 209 is connected with a conductor 296 leading through the armature 211 and front contact of relay 185 to the local brush 297 of the primary selector; said armature 289 when attracted is adapted to separate springs 207, 208 included in the circuit from battery 205 with relay 185, and to engage the spring 208, thereby connecting said relay 185 through its own armature 211, and front contact with said local brush 297.

Now when the selector has been given one upward movement to bring its brushes into engagement with the terminals of a trunk line leading to the first connector of the fourth group, if that connector is busy, the local brush 297 of the trunk line leading to said connector will have potential thereon from the local terminal 298 of said trunk, and current will flow through the local brush 297, armature 211 and front contact of relay 185, winding of relay 185 to earth, maintaining relay 185 energized. Relay 185 in turn will maintain the circuit of the up-stepping magnet 293 intact, and the said magnet 293 will lift the shaft 195 another step, and so on until a trunk line leading to an idle connector is reached, when no current will be found upon the local terminal 298 of such line, and relay 185 will be deprived of current, releasing its armatures. The armatures 210, 184, in retracting restore the continuity of the trunk conductors 152, 153; the armature 212 opens the circuit of the up-stepping magnet 293, and the armature 211 opens the connection of relay 185 with the local brush 297, and engages its back contact connected with a conductor 299 which leads through armature 204 and front contacts of the retaining magnet 194, to the free pole of battery 205, thereby placing by way of local brush 297 a test potential upon the multiples of the local trunk terminals 298.

The line brushes of the shaft 195, which form the terminals of trunk conductors 152, 153, are now in engagement with terminals of the trunk line leading to an idle connector adapted to reach line 1132, said brushes engaging terminals connected with conductors 300, 301, respectively, while the local brush 297, which is connected with the free pole of battery 205, applies battery by way of terminal 298, to the local trunk conductor 302 which leads through the contact springs 303, 304 of a busy test and lock-out relay 305 of the selected connector (Fig. 4) winding of the retaining magnet 306 of the connector, through contact springs closed by the shaft 307 of the connector when in its normal position, to earth. The retaining magnet 306 thereupon attracts its armatures

307^a, 308, armature 307^a completing a locking circuit for the retaining magnet 306, independent of the springs which are separated while the connector shaft 307 is away from normal position. 70

The auxiliary controller.

After the primary selector has selected an idle connector, the third brush 167 (Fig. 6) of the translator and mechanism associated therewith, is arranged to operate the connector to move the brushes on the shaft 307 thereof into the zone or bank of contacts in which is located the terminals of the called party's line. To this end in calling line 80 1132, the auxiliary controller 169 is arranged to cooperate with the brush 167 of the translator to move the brushes of the connector into association with the third bank of contacts in which is located the terminals of line No. 1132 with which connection is to be established. A conductor 311 leads from the wire 269 which is now supplied with current from positive battery 263 by way of the primary controller, to the brush 167 of the translator which now rests upon a second intermediate contact 310 beyond the second tens contact of the set or bank of contacts 168 over which the brush 167 sweeps, said second intermediate contact 95 being connected with a conductor 312 which leads to the last contact terminal 313 upon the auxiliary controller 169, said contact 313 being included in a bank of contacts adapted to be engaged by the contact arm 314 of the controller. The intermediate contact points of the bank 168 are divided into groups of three; the first contact of each group representing the first zone of a connector, being dead; the second contact of each group representing the second zone, being connected with a conductor 312^a to apply battery to the tenth contact point of the controller, while the third contact of each group, representing the third zone of a connector, is 100 connected with a conductor 312 leading to the twentieth contact of the controller. 105

The auxiliary controller has twenty contacts in its bank, and the contact arm 314 is arranged to be moved with the connector brushes to place said connector brushes into operative connection with the proper bank of contacts. Thus if the line wanted were in the first bank of contacts, the auxiliary controller would not operate, since the connector brushes are normally in operative relation to said first bank and the brush 167 would rest upon a dead contact. However, if the line desired were in the second bank of contacts, potential would be applied by 115 the translator brush 167 to the tenth contact of the auxiliary controller, and the controller arm would advance with the connector brushes ten steps, when both would be 120 stopped, leaving the connector brushes in 125 130

operative relation to the second bank. In the present case, calling line 1132, the twentieth contact 313 would have potential applied thereto by the translator brush 167, and the controller arm and connector brushes would be advanced until the controller arm reached point 313, and the connector brushes were placed in operative relation to the third bank of contacts, when 10 both would be stopped.

Sluggish relay 281 associated with the primary controller, whose circuit was completed by the armature 280 of relay 277 after the primary controller and primary selector 15 had completed their operation, in operating applies current from negative battery 315 through the armature 316, and front contact of relay 281, through conductor 319, and thence through the winding of relay 317, contact springs 318 thereof, to conductor 41. The circuit of this relay is not completed until the connector selected by the primary selector is in condition for operation, the circuit extending over conductor 41 to the tip strand 8 and thence over trunk conductors 131, 152, through conductor 174, winding of relay 175, to trunk conductor 153, and thence over the conductor 301 to the connector through springs 320, 321 of a connecting relay 323, to conductor 324, which leads through a resistance 325 to earth through the armature 308 and front contact of the retaining magnet 306, which is now energized. Current in the circuit 35 just traced energizes relay 175, which attracts its armature, applying current from the free pole of battery 189 over conductor 190, through the armature 201 and one of springs 202 of relay 193 to trunk conductor 152, thence through the primary selector, line conductor 300, normally closed contact springs 326, 327, of relay 328, to conductor 329, which leads through the contact springs 330 of a transfer relay 331, rotary stepping magnet 332, to conductor 324, and thence to earth through armature 308, said rotary stepping magnet 332 being energized to give the shaft 307 of the connector an idle movement, which is simply incidental to the operation.

Returning to the auxiliary controller, (Fig. 6) relay 317 is now operated by current from battery 315 in the circuit above traced, and attracts its armature 333, which 55 locks relay 317 to earth in a circuit from battery 315 independent of the connector. Relay 317 also attracts its armature 334, which applies current from the positive battery 335 to conductor 336, which leads to the armature 337 of relay 338. Said relay 338 has two windings, one included in the grounded battery connected with the conductor 312, and the other in a grounded conductor connected with the conductor 312^a,

said relay thereby receiving current from the brush 167 when the same rests on either the second or third contact of a group. In the present case, the brush 167 is resting upon the second intermediate contact past the second tens point, or the third of a group, and current from battery 263 flows by way of conductor 264, brush 164, fourth group of strapped contacts to the fourth contact 265 upon the primary controller, thence by way of arm 166 of the controller, conductors 269 and 311 to the brush 167 of the translator, thence by way of conductor 312, winding of relay 338 to ground. Relay 338 thereupon attracts its armature connecting conductor 336 with conductor 339 which leads through the winding of relay 340, contact springs 341 thereof, to the ground contact of a pulsator 342. And when the ground spring of the pulsator 342 engages such contact, a circuit is completed through relay 340, which attracts its armature 343, separating springs 341, and completing a locking circuit for relay 340 from battery 335, independent of the pulsator 342.

The armature 345 of the relay 340 is connected with conductor 41 while the front contact of said armature is connected with a conductor 346 leading through the armature 347 and back contact of the relay 348, winding of the relay 349 to the battery contact of pulsator 342. Current from the pulsator flows through relay 349 to common wire 41, and thence over strand 8, line conductors 131, 152, conductor 174, relay 175, trunk conductor 153, through the selector contacts 100 and over the line conductor 301 to the connector, where the same passes by way of conductor 324 to earth through the armature of the retaining magnet. Relay 175 in said circuit at the selector is now energized, and applies current from battery 189 over conductor 190, and the trunk conductor 152 through the primary selector and line conductor 300, conductor 329 and rotary stepping magnet 332 and conductor 324 to 110 earth.

The shaft 307 is accordingly rotated to locate the bank of contacts in which the called party's line terminates. Relay 349 of the auxiliary controller, which is in the circuit 115 traced from the pulsator 342, responds to said pulsating current and makes and breaks a circuit from battery 350 through the stepping magnet 351 of the auxiliary controller, advancing the controller arm with the shaft. When the contact arm 314 reaches the contact terminal 313 to which potential is applied by the brush 167, and the brushes on the connector shaft have advanced to a position one step removed from the third bank 120 of contacts, current flows from battery 263 through the brush 167 of the translator, conductor 312, through the arm 314 of the aux-

iliary controller, to earth, by way of a conductor 353 which includes the winding of relay 348. Said relay is thereupon energized and attracts its armature 347, breaking the circuit of the pulsator 342, relay 349 of the auxiliary controller, and the relay 175 associated with the primary selector, which controls the circuit through the rotary stepping magnet 332 of the connector.

10 The back contact of armature 337 of relay 338 is connected with a conductor 354 leading to the tens and units keys. It will be understood that when the line desired terminates in the first bank of 100 lines of 15 a connector, the brush 167 after the translator has been operated, rests upon a dead contact, and relay 338 does not receive current, so that current from battery 335 is applied directly to the tens and units controller, since the service of the auxiliary controller in such event would not be required.

In the present case, however, the line desired is in the third bank of contacts, and during the operation of the auxiliary controller current is removed from conductor 354, since the armature 337 of relay 338 is attracted, but when the relay 348 operates, after the connector has been advanced to the proper bank of terminals, current is applied by the armature 355 of relay 348 from wire 353 and battery 263, to a conductor 356 connected with conductor 354, and current flows over conductor 354 through the armature 356^a and back contact of relay 357 (Fig. 5) to the springs 358 of the tens keys 156 of the tens and units controller.

Tens and units controller.

The tens and units controller is arranged 40 to be set by the operator to be automatically brought into service after the connector has been stepped around until its brushes rest one step from the first vertical row of line terminals of the selected bank. In each 45 bank of one hundred lines there are ten vertical rows of ten lines each, and the depressed tens key 156 controls the advance of the connector brushes around to the vertical row which contains the terminal of the 50 line desired at which time the depressed units key is brought into service to operate mechanism adapted to step the connector brushes up to the desired line terminal.

In calling line 1132, as before stated, the 55 key III of the tens keys and the key II of the units keys were operated, said keys remaining in their depressed positions under the control of release magnets 359, 360 respectively. The controller is provided with 60 a bank of contacts provided with tens terminals between which are located intermediate terminals or units terminals, and the brush 361 carried by shaft 362 is arranged to sweep over said terminals; the shaft be-

ing advanced in long steps between the tens 65 terminals by a long step magnet 363, and over the intermediate terminals in short steps by magnet 364. A retaining magnet is provided for the shaft 362, receiving current from the feed wire 48, as referred to 70 hereinbefore.

Operation of mechanism controlled by tens keys.

In calling line No. 1132, key III of the 75 tens keys was depressed, and when battery was applied to springs 358 as previously described, said spring 358 of key III, in engaging spring 365 applies current from battery 263 to the fourth tens terminal of 80 the bank. Spring 365 in engaging its contact 366 also applies current from battery 263 to conductor 367, which leads through the winding of relay 368 and contact springs associated with said relay, to the 85 ground contact of pulsator 369, and when the ground spring of said pulsator engages its contact, a circuit is completed for relay 368, which draws up its armatures, armature 370 completing a locking circuit for 90 said relay independent of the pulsator.

The armature 371 of said relay in its attracted position completes the continuity of a conductor 372 leading from the battery contact of a pulsator 373, through relay 374, 95 armature 375, and back contact of a relay 376, to the common wire 41, and current flows from pulsator 373, over conductors 372, 41, 8, 131, 152, 174, 153, 301, 324, to earth, this circuit including relay 175 which 100 applies current to the rotary stepping magnet 332 of the connector in the circuit formed by conductors 190, 152, 300, 329, 324, to earth, said stepping magnet responding to the pulsations moving the brushes on the 105 shaft 307 of the connector past the vertical rows of terminals in the selected bank. Relay 374 in the circuit traced from pulsator 373, makes and breaks a circuit 376^a for the long step magnet 363 of the tens and units 110 controller, which advances the shaft 362 carrying brush 361 long steps over its bank of contacts. When the brush 361 reaches the fourth tens terminal and the connector brushes have been given four steps and lie 115 below the vertical row of contacts containing the terminals of line 1132, the current which has been applied to the fourth tens terminal of the controller by the depressed tens key III, flows over the brush 361, conductor 377 connected therewith, through the armature 378 and back contact of sluggish relay 357, winding 379 of relay 376 to earth. Relay 376 is now operated and attracts its armatures, the armature 375 opening the circuit 120 of the pulsator including the relay 374 of the controller, and the relay 175 of the primary selector, which controls the circuit of

125

the rotary magnet of the connector. The armature 380 of relay 376 in its attracted movement, completes a locking circuit for the relay 376, said circuit extending from 5 the feed wire 48 through conductor 381, sluggish relay 357, and a winding of relay 376 to earth.

The armature 382 of the relay 376 in its attracted movement completes the continuity 10 of the conductor 383 leading from the wire 377, which is connected with the battery through the brush 361, through armature 384 and its back contact of relay 357 to the common wire 44. And before the sluggish 15 relay 357 has had time to operate, an impulse of positive current is applied to the common wire 44, said current flowing from the free pole of grounded positive battery 263, conductors 264, 269, 311, 312, 353, 356, 20 354, armature 356^a, and back contact of relay 357, through springs 358, 365 of the tens key III, brush 361 of the tens and units controller, conductors 377, 383, armature 382 and front contact of relay 376, and armature 25 384 and back contact of relay 357 to common wire 44, thence over the line conductors 9, 132, 153 to the distant office, thence over the local wire 284, contact springs 285, 286, of relay 183, through the winding of 30 polarized relay 178 to earth. Said relay thereupon tilts its armature in a counter-clockwise direction, applying current from battery 288, through the springs 287, 177, conductor 174, to the line conductor 153, 35 thence through the primary selector to line conductors 301 and connector, conductor 324, to conductor 387 which leads through contact springs 385, of relay 331, winding of said relay, contact springs 386, of the relay 323, to conductor 324 and earth.

The transfer relay 331 is now operated to bring the lifting magnet 388 of the connector into connection with the line conductor 300. The armature 389 of said transfer relay 45 when attracted locks the relay 331 in a circuit from conductor 302, which is connected with the battery 205, conductors 387, 324, to ground. The armature 389^a of the transfer relay is connected with a conductor 390 50 which leads through the armature and back contact of a relay 391, winding of the lifting magnet 388, to conductors 387 and 324 and earth. Said armature 389^a when attracted separates contact springs 330, engaging the member thereof connected through conductors 329 and contact springs 326, 327 of relay 328 with line conductor 300. The stepping magnet 388 is now in condition to receive impulses to move the 55 connector shaft 307 upwardly.

Operation of mechanism controlled by units keys.

The sluggish relay 357 above referred to 60 has now been operated, attracting its ar-

matures 384, 356^a, and 378. The armature 356^a, which at this time is connected with positive battery 263, in engaging its front contact applies battery to conductor 392 leading to the main springs 393 of the units 70 keys. Since the key II of the units keys is depressed, its contact spring 393 will rest in electrical engagement with springs 394 and 395, spring 394 being connected with a conductor leading to the third intermediate 75 terminal past the fourth tens terminal of the controller bank of contacts, said terminal corresponding to the number thirty-two. The spring 395 will apply current from the conductor 392 to the conductor 396 80 which extends through the winding of relay 397, contact springs associated therewith, to the ground contact of a pulsator 398; and when the ground spring of the pulsator engages said ground contact, the 85 circuit will be completed for relay 397, which, in attracting its armature 399, completes a locking circuit for itself independent of the pulsator. Said relay also attracts its armature 400, which completes the 90 continuity of a conductor 401, leading from the battery contact of a pulsator 402, through the winding of a relay 403, armature 404 and back contact of a relay 33, to common wire 41, and as the battery spring 95 of the pulsator 402 intermittently engages its contact, pulsating current will flow over the conductor 401 including relay 403, conductors 41, 8, 131, 152, 174, including relay 175, conductors 153, 301, 324, to earth. 100 Relay 175 will respond to the pulsations in said circuit and apply pulsations from battery 189 by way of conductors 190, 152, 300, 329, 390, 387, 324, to earth, said circuit including the lifting magnet 388 of the connector, which gives the shaft 307 of the connector its upward movement.

The relay 403 in the circuit of the pulsator 402 intermittently makes and breaks a circuit 406 for the short-step magnet 364 110 of the tens and units controller, said magnet 364 thereupon advancing the shaft 362 and brush 361 in short steps over the intermediate terminals. When the brush 361 reaches the third intermediate terminal corresponding to units key II, and the brushes of the connector have been lifted to the terminal of line 1132, current from battery 263 will flow by way of conductors 264, 269, 311, 312, 353, 356, 354, 392, brush 361 of 115 the tens and units controller, conductor 377, to the armature 378 of relay 357, whose front contact is connected with a conductor 407 leading to earth through the winding 408 of the relay 33, which relay thereupon 120 is energized and attracts its armature 404, opening the circuit of the pulsator 402 before traced, including the relay 403, and the relay 175 at the distant office which controls the circuit of the lifting magnet of 125 130

the connector. The shaft of the connector now rests with its brushes in engagement with the terminals of line No. 1132.

The armature 32 of said relay 33 in its attractive movement opens the locking circuit including the relay 26 (which applies current from battery 27 to the feed wire 48) and also relay 31, which in releasing its armatures 39, 40, restores the continuity of the link conductors 8, 9, disconnecting therefrom conductors 41, 44, respectively. The armature 405 of the relay 33 is connected with the feed wire 48, the front contact of said armature being connected to earth through a winding of relay 33 and with a conductor 409, which leads to the front contact of armature 384 of relay 357, said armature 384 being connected with the wire 44. After relay 33 has drawn up its armatures, but before the armatures of relays 26 and 31 have had time to retract, an impulse of current from battery 27 passes through front contact of armature 47 of relay 26 to feed wire 48, thence to armature 405 of relay 33, conductor 409, front contact of armature 384 of relay 357 to the sender lead 44, thence through contacts of relays 21 and 31 to the conductor 9 of the connecting circuit, thence to brush 52 of the office selector, contact 125, conductor 132, to brush 129 of the trunk selector, conductor 153, through one winding of the repeating coil at the primary selector to conductor 284, through contact 286 of relay 183 and thence through the winding of relay 178 to earth.

Relay 178 in responding to said negative current tilts its armature in a clockwise direction, and applies current from grounded battery 411 through the springs 412, 180 to conductor 174, and line conductors 153, 301 for the purpose of the busy test to be hereinafter explained. Said armature also closes contact springs 413, 414, applying current from battery 411 to a conductor 415 which leads through a high resistance winding 416 of relay 417, to conductor 174, current from battery 411 finding a path through the winding 416 by way of conductor 174 and line conductors 152, 181 and 8, through the repeating coil associated with the operator's connecting circuit to the grounded pole of battery 12.

Relay 417 is provided with an armature 418 which, when attracted, completes a circuit from the free pole of battery 196, through the winding of relay 183, conductor 419, to earth; said relay 183 thereupon attracting its armatures 420, 421, 422. The armature 422 is adapted when attracted to separate springs 285, 286, and break the connection of polarized relay 178 with the trunk conductor 153. Said armature is connected with a conductor 423 which leads to

the conductor 415, and when said armature 65 is attracted it engages the contact spring 285 and includes the winding 416 of the relay 417 in a bridge around the condenser which is included between two windings of the repeating coil, said bridge including conductors 174, 415, winding 416 of relay 417, conductor 423, armature 422 and contact spring 285 of relay 183, and conductor 284. The winding 416 of relay 417 now receives current in metallic circuit from the battery 75 12 included in the bridge of the operator's connecting circuit.

The armature 420 of relay 183 when attracted separates the springs 181, 182, engaging spring 182 to complete the continuity 80 of the portion of trunk conductor 153 between the repeating coil and the primary selector; while the armature 421 in its attractive movement separates springs 197, 198, opening the circuit of relay 193, which 85 releases its armature 201, 199; armature 201 permitting the reengagement of springs 202 to complete the continuity of the portion of the trunk conductor 152 extending between the repeating coil and selector, armature 199 opening at another point the circuit of relay 193. The said armature 421 of relay 183 is adapted when attracted to engage the spring 197 and apply battery 95 196 to the local wire 190 containing the retaining magnet of the selector, independently of the relay 193, which is now deenergized.

It should be noted at this point that the resistance of the winding 416 of the relay 100 417 in the metallic circuit with the battery 12 at the connecting circuit, is too great to permit the operation of the supervisory relay representing the called line, which accordingly remains inert, maintaining the 105 display of the supervisory lamp representing the called line.

Restoration of sending apparatus.

The relay 26 shortly after the impulse 110 passed from battery 27 over the conductor 44 to operate the relay 417, became de-energized, and retracted its armatures 47, 424, 24, the armature 47 in its retractive movement breaking the connection of battery 27 with feed wire 48, thereby opening the circuits of the holding magnets of the controllers and translating mechanism, permitting the restoration of the contact arms thereof to normal position. The armature 120 424 of said relay is connected with the free pole of battery 27, and is adapted during its retractive movement to momentarily make electrical contact with both members of a pair of contacts 426, one member whereof is connected with a conductor 427 leading in multiple branches through the release magnets 80, 221, 428, 359 and 360, respec-

tively, of the office, thousands, hundreds, tens and units keys respectively, whereupon the latch bars of said keys are operated and the depressed keys restored to normal position. Current is now removed from all the mechanism of the sending apparatus, and the lamp 509 of board A is extinguished, indicating to the operator that the sending apparatus may be taken for use with another connecting circuit if desired. The armature 24 of relay 26 at the A board in retracting, opens the circuit 499 through the winding 497 of relay 21 of the connecting circuit II, which relay will thereupon become de-energized and retract its armatures, restoring the operative relation of connecting circuit II with the sending apparatus A. The armature 500 of relay 31 of connecting circuit I in its retractive movement, restores the connection of battery 59 with conductor 499.

Test of the called line.

When the polarized relay 178 associated with the primary selector received its impulse of negative current as above described, it applied current from battery 411 through contact springs 412, 180, conductor 174, contacts 181, 182, of relay 183, before said relay was operated by relay 417, said current passing thence over the line conductors 153, 301, through the contact springs 320, 321, to conductor 324, through contact springs 429, closed at the first upward movement of the connector, conductor 430, winding of relay 431, conductors 329, 324, to ground. The resistance 325 is provided in order to prevent the grounded armature of relay 305 from short circuiting the transfer relay 331 and to keep relay 431 out of circuit when the impulse is transmitted over the line conductor 301 to operate the transfer relay 331, while still affording a path to ground through relay 175, from the sending apparatus.

The relay 431 responds to the impulse above referred to, and attracts its armature 432, completing the continuity of a test conductor 433, leading from the local brush 434 of the connector through the connecting relay 323, and relay 391 to conductors 430, 329, 324 and to earth.

The telephone line No. 1132 indicated in Fig. 4 leads in two limbs to its line terminals upon the connector, its local terminal being connected in multiple to other local terminals representing the said line on other connectors, and to the test thimble of an answering jack, and thence to earth through a battery; the equipment being the same as that of the calling line. Now in case the line is made busy either at the answering jack of such line, or at a connector making connection with said line, a

shunt will be established around the test conductor 433 of another connector attempting to make connection with such line, and the relay 323 will not receive sufficient current for its operation. If, therefore, the line with which connection is desired is busy, after the relay 431 is operated to attract its armatures 432, and 435, and relay 323 fails to respond, current will be applied from a pulsator 436 by way of conductor 437, contact springs 438 controlled by relay 323, through an armature and back contact of relay 391, armature 435 and front contact of relay 431 to earth through the winding of the busy test and lockout relay 305, which is sluggish, to provide a time interval wherein the relay 323 may respond if the line is free.

The armature 439 of the relay 305 is connected with the conductor 437, and in its attractive movement separates springs 303, 304, to break the circuit of the retaining magnet of the connector and permit the restoration of said connector to normal condition, said armature engaging the spring 303, which is connected by way of the local conductor 302, and the contacts 297, 298 of the selector, with battery 205, to provide a locking circuit for the relay 305 independent of the apparatus of the connector. The armature 440 is adapted when attracted to complete the continuity of the conductor 441 leading from line conductor 301 to a busy signal apparatus, said armature 440 being connected with a vibrating arm adapted to intermittently engage a contact connected by conductor 442 to earth, and with a contact connected with a conductor 443 leading through a busy tone apparatus to earth, so that the busy tone apparatus and ground conductor 442 are alternately applied to the line conductor 301, and so to the ring strand 9 of the connecting circuit, thereby applying a distinctive busy tone to the calling subscriber's telephone set and to the operator's telephone set when she listens in by means of her listening key.

The intermittent ground applied to the line conductors 301 and 153 is arranged to cause a peculiar flashing of the supervisory signal representing the called line, and this result is accomplished in the following way: The resistance of the winding 416 of relay 417, which is included with the supervisory relay representing the called line in the metallic circuit with the battery 12 at the connecting circuit, is too great to permit the energization of the said supervisory relay. Said relay 417 is provided with a low resistance winding 444, included in a shunt 445, about the high resistance winding 416 of said relay, said shunt being controlled by a relay 446 included in the trunk conductor 153 in the path of current from

grounded battery 203; and when the ground is applied by the busy test apparatus to the conductors 301, 153, relay 446 is intermittently energized and makes and breaks the shunt 445, including the winding 444, whereupon the supervisory relay of the called line intermittently receives sufficient current to cause the same to vibrate its armature, and the supervisory lamp is caused to give a distinctive signal indicating to the operator that the called line is busy.

The feature of testing the called line just described forms no part of the present invention, but is described and claimed in an application of James L. McQuarrie and Albert M. Bullard, Serial No. 336,401, filed September 27th, 1906.

Signaling the called party.

The line conductor 300 normally leads from the primary selector through normally separated contact springs 326 and armature 477 of relay 328, armature 448 and back contact of the ringing relay 449 to the line brush 450 upon the shaft 307 of the connector; while the line conductor 301 leads through the normally separated front contact spring 320 and armature 451 of the connecting relay 323, through the armature 452 and back contact of the ringing relay 449 to the line brush 453. Assume now that the line number 1132, with which the connector has united the trunk and the connecting circuits is free, a circuit will be completed by the local connector contacts leading from the battery associated with the called line, through test conductor 433, connecting relay 323, polarized relay 391, to earth through the armature 432 and front contact of the relay 431, which relay is maintained energized after the relay 183 is excited, through whose normal contacts 181, 182 the initial current from battery 411 passed, by reason of the contact of armature 420 of relay 183 connected with battery 203 in the trunk circuit, with the spring 182, thus substituting battery 203 to maintain an operative circuit for the relay 431. This current in the testing conductor from the battery of the idle called line is sufficient to energize said relay 323, which draws up its armatures 451, 455 and 456. The armature 451 separates springs 320, 321, engaging spring 320 to complete the continuity of line conductor 301, opening the circuits and disconnecting the local apparatus of the connector from the limb 301; the armature 455 is connected with a conductor 457 which leads through the winding 458 to the test conductor 433 between the connecting relay 323 and relay 391; said armature when attracted engages the member of springs 336 which is connected with the portion of conductor 387 leading to the conductor 324 and

earth, so that the continuity of the test conductor is maintained independently of the armature 432 of relay 431, current flowing from the battery of the called party's line over the conductor 433 through relay 323, conductors 457, 387, and 324 to earth, maintaining the connecting relay 323 energized.

The remaining armature 456 of the connecting relay forms the terminal of a conductor 459 leading through contacts 460 of the ringing relay 449, winding of said relay, contacts 461 of relay 328, armature 432 and back contact of relay 431, which is now deenergized, to conductors 430, 329 and 324 and earth. Said armature 456 in its attractive movement separates springs 438, preventing the operation of the busy test apparatus and engaging the member of said springs which leads to the pulsator 436, so that an impulse of current passes from said pulsator over conductors 437, 459, 430, 329, 432 to earth, operating relay 449. Relay 449, in attracting its armature 462, which is connected with battery 463, completes a locking circuit 459, 430, 329, 324, for said relay 449, under the control of springs 461 of relay 328. The armatures 448, 452, with their back contacts are normally included in the line conductors 300, 301, the armatures being connected with the portions of said conductors leading directly to the brushes 450, 453, respectively.

The armature 448 of relay 449 when attracted engages a front contact connected with a conductor 464, leading through a winding of a relay 465 to the armature of relay 458, which is now energized, said armature engaging a front contact connected with generator 466 of positive current. The armature 452 of relay 449 when attracted engages its front contact, which is connected with the conductor 467 leading through a winding of the relay 465, conductors 329, 324 to earth. Therefore, when the relay 323 operates, it completes a circuit for relay 449 which locks up from battery 463, and ringing current is applied to the line from the free pole of generator 466, conductor 464, winding of relay 465, to the armature 448 and front contact of relay 449, line conductor 300, line brush 450 of the connector, out over a limb of line 1132 and through the bell at the substation, said current returning over the other limb of the line 1132 through brush 453 of the connector, and thence over line conductor 301, armature 452 and front contact of relay 449, conductor 467, winding of relay 465 to conductors 329, 324 and earth.

The relay 465 included in the said ringing circuit above traced is not responsive to the current flowing in the circuit owing to the high resistance of the bell at the substation, but when the called subscriber re-

Turning now to the distant office, the high resistance winding 416 of relay 417 was deprived of current the instant the office selector commenced its return to normal condition. Said relay thereupon retracted its armature and opened the local circuit of relay 183, which restored the normal circuit conditions of the apparatus of the trunk lines and removed current from the retaining magnet 194 of the primary selector, 10 which thereupon released the shaft 195 of the selector, and removed current from the relay 209, permitting it to restore the apparatus of the selector to normal condition and remove the potential of battery 205, 15 from local brush 297 and local conductor 302 leading to the connector and retaining magnet of said connector. Said retaining magnet of the connector thereupon released its armatures, permitting the restoration of the connector to normal condition.

The armature 308 of the retaining magnet of the connector in retracting opens the locking circuit of relay 328 which thereupon releases its armatures, armature 447 opening the line conductor 300, to maintain brush 450 dead during the return of the connector. In like manner, the brush 453 of the connector is dead during its return movement, since relay 323 is deprived of current the instant the return movement starts, and the armature 451 of said relay 323 in retracting breaks the continuity of the line conductor 301.

It will be understood that while a number of batteries are shown throughout the drawings, batteries of the same polarity may be and usually are, in practice, one and the same. In like manner while a number of pulsators are shown, in practice, pulsators having the same speed and voltage may be one and the same.

We claim:

1. The combination with a plurality of connecting circuits, of switching mechanism associated therewith, a series of sending mechanisms, and means whereby the first idle sending mechanism of the series may be automatically associated with any one of said circuits.

2. The combination with a number of connecting circuits, of a mechanical line switching mechanism for each circuit, a series of sending mechanisms, and means whereby the first idle sending mechanism may be automatically associated with any one of said circuits taken for use.

3. The combination with a number of connecting circuits, of mechanical line switching mechanism for said circuits, a number of sending mechanisms, said circuits being all normally in operative relation to one of said sending mechanisms, and means operated when said mechanism is

taken for use by one circuit, for transferring 65 the remaining circuits into operative relation to an idle sending mechanism.

4. The combination with a number of connecting circuits, of line switching mechanism for said circuits, a number of sending 70 mechanisms, and means whereby each of said circuits, when used, automatically employs an idle sending mechanism.

5. The combination with a number of connecting circuits, of mechanical switching 75 mechanism for said circuits, a number of sending mechanisms, said circuits being all normally in operative relation to one of said sending mechanisms, automatic means, operated when said sending mechanism is 80 taken for use by one circuit, for transferring the remaining circuits into operative relation to an idle sending mechanism, and means, operated when said busy sending mechanism has completed its work, for restoring said remaining circuits into operative relation to said sending mechanism.

6. The combination with a group of connecting circuits, of a plurality of senders, automatic means, controlled in the use of 90 any of said connecting circuits, adapted to bring one of said senders into operative relation to such connecting circuit, and automatic means controlled by the use of one sender, for switching another sender into 95 condition to serve any of the other connecting circuits while the first sender is in use.

7. The combination with a pair of connecting circuits, of mechanical switching mechanism for each connecting circuit, a 100 pair of keyboards, and means for automatically associating an idle one of said keyboards with either connecting circuit taken for use, to operate its switching mechanism.

8. The combination with a pair of connecting circuits, of line switching mechanism for said connecting circuits, a pair of keyboards, means for associating an idle one of said keyboards with either of said connecting circuits, automatic means for locking out the other connecting circuit from such keyboard, and means controlled by said automatic means for associating said other keyboard with said other connecting circuit.

9. The combination with a pair of connecting circuits, of line switching mechanism for said circuits, a pair of controlling mechanisms, and a key for each connecting circuit adapted to tie an idle one of said 120 mechanisms to its circuit.

10. The combination with a pair of connecting circuits, of line switching mechanism for said connecting circuits, a pair of controlling mechanisms, an operator's key 125 for each connecting circuit, means controlled by each key for associating the first controlling mechanism with its connecting cir-

cuit if said mechanism is idle, and means, actuated in case one of said keys has tied said first mentioned controlling mechanism to its connecting circuit, for causing the key 5 of the other connecting circuit when operated to tie the second controlling mechanism to said other connecting circuit.

11. The combination with a pair of connecting circuits, of mechanical line switching mechanism for said circuits, a pair of sending mechanisms, a key associated with each of said connecting circuits, each key being adapted, when operated, to associate the first of said sending mechanisms with its connecting circuit, and electromagnetic mechanism, actuated upon the operation of either key, to cause said other key, if operated while the first sending mechanism is busy, to associate the second sending mechanism with its connecting circuit.

12. The combination with a pair of connecting circuits, of a mechanical line switching mechanism for said connecting circuit, a pair of sending mechanisms, a key associated with each connecting circuit, a controlling relay for one of said mechanisms, a circuit for said relay adapted to be completed by either key to associate said mechanism with its cord circuit, and means 25 actuated by said controlling relay, when operated by either key, for causing the other key, if operated while said mechanism is in use, to associate the other sending mechanism with the connecting circuit of 30 said key.

13. The combination with a pair of connecting circuits, of mechanical line switching mechanism for said circuits, a pair of sending mechanisms, an operator's key for 40 each connecting circuit, and circuits normally controlled by each key for associating one of said mechanisms with the connecting circuit of such key, a relay associated with each connecting circuit, circuits associated 45 with said other controlling mechanism, a circuit for the said relay of one connecting circuit, completed by the operation of the key at the other connecting circuit in associating the said first mentioned sending mechanism therewith, and means operated by said relay for transferring the key of its connecting circuit to the control of the circuits of the said other sending mechanism.

14. The combination with a pair of connecting circuits, of mechanical line switching mechanism for said circuits, a pair of sending mechanisms, a relay controlling the first sending mechanism, a key associated 60 with said first connecting circuit, a circuit for said controlling relay completed by said key when operated, a key associated with said other connecting circuit also normally controlling the circuit of said controlling

relay, a controlling relay for said other 65 sending mechanism, a relay 21 associated with each connecting circuit, a circuit for the relay 21 of an idle connecting circuit completed by the controlling relay of the first sending mechanism upon the operation 70 of the key at the other connecting circuit, a circuit for the controlling relay of the other sending mechanism, and means operated by said relay 21 of an idle connecting circuit for locking out the key of such connecting circuit from the circuit of the controlling relay of the first sending mechanism and for placing said key in control of the circuit of the controlling relay of the second sending mechanism.

15. The combination with a pair of connecting circuits, of a mechanical line switching mechanism for said connecting circuits, a pair of sending mechanisms, means whereby either connecting circuit may associate therewith the first sending mechanism, means actuated when said first sending mechanism is taken for use by one connecting circuit for placing the other sending mechanism in condition to be associated with the other or idle connecting circuit, and for locking out said idle connecting circuit from the first sending mechanism, and means operated when the first sending mechanism has completed its work for restoring the operative 95 relation of said second connecting circuit and first sending mechanism.

16. The combination with a pair of connecting circuits, of line switching mechanism associated with said circuits, a controlling mechanism, means for associating said mechanism with either connecting circuit, a second controlling mechanism, means automatically operated by said first controlling mechanism while in use with one 100 connecting circuit for bringing said second mechanism into operative condition to be associated with the other circuit, and means automatically operated when said second controlling mechanism is taken for 105 use by said other circuit for maintaining said second controlling mechanism in association with said other circuit independent of the first mentioned controlling mechanism.

17. The combination with a pair of connecting circuits, of mechanical line switching mechanism for said circuits, a pair of controlling mechanisms, a controlling relay for the first controlling mechanism, a key for each connecting circuit, a circuit for said controlling relay adapted to be completed at either key, a relay 21 associated with each connecting circuit, a circuit for the relay 21 of one connecting circuit completed by said controlling relay when operated by the key of the other connecting circuit, a controlling relay for the other controlling mechanism 125

- and a circuit therefor, means operated by relay 21 of the idle cord circuit for transferring the control of the circuit of the controlling relay of the second controlling mechanism to the key of such idle connecting circuit, a relay in the circuit of the controlling relay of the first controlling mechanism adapted to complete a locking circuit for said controlling relay independent of the connecting circuit key initially operating the same, and means automatically operated by said first controlling mechanism at the end of its operation for opening the locking circuit of its controlling relay, and thereby restoring the key of the idle connecting circuit to the control of the controlling relay circuit of the first controlling mechanism.
18. The combination with a pair of connecting circuits, of mechanical line switching mechanism for said circuits, a pair of controlling mechanisms, a controlling relay for the first controlling mechanism, a circuit for said relay, a key associated with each connecting circuit controlling said circuit, a relay 21 associated with each connecting circuit, a circuit for the relay 21 of one connecting circuit completed by said controlling relay when its circuit is completed by the key at the other connecting circuit, a locking circuit for the controlling relay completed during the operation of the first controlling mechanism, a controlling relay for the second controlling mechanism, a circuit therefor, means controlled by the operation of relay 21 of the idle connecting circuit for transferring the control of the circuit of the second mentioned controlling relay to the key of such connecting circuit, and a locking circuit for said relay 21 of the idle connecting circuit, completed upon the operation of the key of such connecting circuit, adapted to maintain the association of the said second controlling relay with the second connecting circuit independent of the first controlling mechanism.
19. In a semi-mechanical telephone switching system, the combination with a group of connecting circuits, of a plurality of senders, an automatic sender-seizing switch for each connecting circuit, an automatic transfer switch associated with each seizing switch, adapted to govern the connection of the different senders thereto, and means controlled in the use of one sender by any connecting circuit, for operating the transfer switches associated with the other connecting circuits, whereby another sender is available for any of such other circuits.
20. In a semi-mechanical switching system, the combination with a group of operators' connecting circuits, of two sets of sending leads, a sender seizing relay 31 associated with each connecting circuit, a transfer relay 21 having contacts whereby either set of sender leads are extended to the contacts of said relay 31 according as said relay 21 is normal or excited, a relay 26 excited in the use of one of said senders, and means controlled by said relay for exciting all of said transfer relays.
21. In a semi-mechanical switching system, the combination with operators' connecting circuits, of two senders, each having a set of sending leads extending to all the connecting circuits of a group, a sender-seizing relay for each connecting circuit, a transfer relay associated therewith adapted to bring the contacts of its seizing relay into operative relation to one or the other alternatively, of said sets of sending leads, according as said transfer relay is normal or excited, a circuit 499 from which all said transfer relays are connected in multiple branches controlled by back contacts of their respective seizing-relays, and means actuated in the operation of any seizing relay for completing said circuit 499 to excite the transfer relays of the other connecting circuits.
22. In a telephone system, the combination with a plurality of subscribers' lines, of line selecting apparatus, a plurality of senders common to a plurality of said lines, any one of which may control selection, a switch adapted in the operation of the system to assume different circuit controlling positions, said switch during such movement operatively associating one or another of the controlling apparatus with the selecting apparatus.
23. In a telephone exchange system, the combination with a plurality of lines, of line selecting apparatus, of two senders common to said lines, each of which may control selection, and a switch adapted in the operation of the system to assume different circuit controlling positions, said switch in one position rendering one sender effective, and in another position bringing the other sender into service.
24. In a telephone line selecting system, a plurality of senders and a switch adapted in its normal position to render one sender apparatus effective and in another position to bring another sender apparatus into service.
25. In a telephone exchange system, the combination with subscribers' lines, connecting circuits and switches for connecting calling lines with connecting circuits, of selectors adapted to extend said connecting circuits to other lines, a plurality of selector controllers, and automatic switching means for associating idle controllers one after another with the said connecting circuits when they are taken for use.
26. In a telephone exchange system, the combination with subscribers' lines, con-

necting circuits and switches for connecting calling lines with connecting circuits, of selectors adapted to extend said connecting circuits to other lines, a plurality of selector controllers, automatic switching means for associating idle controllers one after another with the said connecting circuits when they are taken for use, and means for disconnecting said controllers from said connecting circuits upon the operation of the selectors.

27. In a connective system, the combination of subscribers' lines; trunks cooperating with the terminals of said subscribers' lines; operators' selective equipments for the control of said trunks; and automatic switches associated with said trunks and with said operators' equipments, and adapted to connect an idle operator's equipment with a trunk requiring attention, substantially as described.

28. In a connective system, the combination of subscribers' lines; trunks cooperating with the terminals of said subscribers' lines; operators' equipments for the control of said trunks; automatic switches associated with said trunks and with said operator's equipments and adapted to connect an idle operator's equipment with a trunk requiring attention; and means for automatically disconnecting the operator's equipment from a trunk after the desired connection has been set up, substantially as described.

35. 29. In a telephone system, an operator's cord circuit, a supervisory signal therefor, trunk lines accessible to said cord circuit and adapted to be seized thereby, a calling device common to said trunk lines, means controlled by the seizure of one of said trunk lines for automatically connecting said calling device thereto, means controlled by the operator for disconnecting said device from the trunk line, and means controlled by the response of a called subscriber for operating said signal.

30. In a telephone system, an operator's cord circuit, a supervisory signal therefor, trunk lines accessible to said cord circuit and adapted to be seized thereby, a calling device common to said trunk lines, electromagnetic means controlled by the seizure of one of said trunk lines for automatically connecting said calling device thereto, means controlled by the operator for disconnecting said device from the trunk line, and means controlled by the response of a called subscriber for operating said signal.

31. In a telephone system, an operator's cord circuit, a supervisory signal therefor, trunk lines accessible to said cord circuit and adapted to be seized thereby, a calling device common to said trunk lines, a relay

controlled by the seizure of one of said trunk lines for automatically connecting said calling device thereto, means controlled by the operator for disconnecting said device from the trunk line, and means controlled by the response of a called subscriber for operating said signal.

32. In a telephone system, trunk lines, a calling device common to said trunk lines, means controlled by the seizure of one of said trunk lines for bringing said calling device into operative relation with the seized trunk line, and means controlled either automatically or by the operator for removing the calling device from operative relation with the trunk.

33. In a telephone exchange system, a number of subscribers' lines, a number of trunks less than the number of lines for interconnecting said lines, an operator's impulse sending device associated with said trunks, and means associated with said sending device for automatically connecting with any busy trunk together with restoring means for said connecting means.

34. A telephone exchange system comprising subscribers' lines, automatic switches and trunks for extending the circuits of said lines, an operator's impulse sending device for controlling certain of said switches in extending such circuits, means for automatically establishing connection between said sending device and any busy one of certain of said trunks, and means for automatically freeing said device for further use as soon as said control has been exercised.

35. A telephone system including selective switches, telephone lines adapted to be interconnected for conversations by said switches, operators' impulse transmitters for adjusting said switches, trunk lines extending from points adjacent to said switches to said transmitters, a trunk line being provided individual to each transmitter, automatic switching means intermediate of said switches, and trunk lines for interchangeably connecting said trunk lines and switches.

36. A telephone system including selective switches, telephone lines adapted to be interconnected for conversations by said switches, operators' impulse transmitters for adjusting said switches, trunk lines extending from points adjacent to said switches to said transmitters, a trunk line being provided individual to each transmitter, automatic switching means intermediate of said switches and trunk lines for interchangeably connecting said trunk line and switches, and means automatically controlled at said transmitters for disconnecting said trunk lines and switches.

37. A telephone system including tele-

phone lines, directively operable selective switches including first selectors for connecting said lines in pairs for conversation, operators' impulse transmitters for adjusting
5 said switches, trunk lines individual to said transmitters respectively, extending to points adjacent to said selectors, a signal for each said trunk line, and automatic means intermediate of said trunk lines and select-
10 tors for interchangeably connecting the same.

In witness whereof, we hereunto subscribe

our names this 15th day of January, and 17th day of January, 1907, respectively.
